DESIGN FOR A SALAD BOWL

Herman L. Steinhilber, New York, N. Y., assignor to McCrory Stores Corporation, New York, N. Y., a corporation of Delaware

Application July 6, 1940, Serial No. 93,480

Term of patent 7 years

To all whom it may concern:

Be it known that I, Herman L. Steinhilber, a citizen of the United States and a resident of New York city, in the county of New York and State of New York, have invented a new, original, and ornamental Design for a Salad Bowl, of which the following is a specification, reference being had to the accompanying drawing, forming a part thereof.

In the drawing:

I claim:

The ornamental design for a salad bowl, as shown.

HERMAN L. STEINHILBER.
